(57) **CLAIM**

I claim the ornamental design for a “gasoline pump handle clip,” as shown and described.

DESCRIPTION

FIG. 1 is a perspective view of a gasoline pump handle clip showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a first end view thereof; and,

FIG. 7 is a second end view thereof.
